UNITED STATES PATENT OFFICE.

RALPH SEVERINO, OF AUSTIN, PENNSYLVANIA.

MAIL-DELIVERY APPARATUS.

Application filed May 14, 1923. Serial No. 638,743.

This invention relates to a mail delivery apparatus adapted to be installed in banks, office buildings, or apartment houses, to enable the mail carrier to properly deliver the mail without the necessity of visiting each separate office or apartment.

The invention has for an object to provide a relatively simple apparatus of this type which comprises a delivery box divided 10 into a number of compartments into which the mail may be placed by the mail carrier and which will be moved by a suitable conveyor member to the different offices or apartments.

15 For further comprehension of the invention, and of the objects and advantages thereof, reference will be had to the following description and accompanying drawings, and to the appended claims in which the 20 various novel features of the invention are more particularly set forth.

Fig. 1 of the drawings is a diagrammatic elevation showing my improved mail delivery apparatus.

25 Fig. 2 is a detail elevational view showing the means for driving the conveyor.

Fig. 3 is a plan view of the delivery box.

Fig. 4 is an end view thereof, indicating the conveyor chain in transverse section.

30 Fig. 5 is a face view thereof.

Fig. 6 is a fragmentary rear view.

Fig. 7 is a fragmentary horizontal sectional view indicating the arrangement of the guide pipes for the cords that operate 35 the contact-controlling cams.

In Fig. 1 of the drawings I have indicated in diagrammatic lines a building such as an office building, the lines 10 indicating the wall partitions. In one wall of each compartment is an opening 12 through which the mail is received by the occupant of the compartment, while adjacent the entrance to the building is an opening 13 through which the mail carrier inserts the mail into the 40 delivery box. In constructing my improved apparatus I provide a pair of sprocket chains 15 which are looped over suitable sprocket wheels 16 arranged in pairs, the respective wheels of each pair being mounted on separate, axially aligned, stub shafts to leave the space between the two wheels free for the passage of the delivery or carrier box. The chains may be driven by an electric motor 17 whose shaft 18 is connected by sprocket 50 chains 19 with a pair of the stub shafts supporting the sprocket wheels. It will be

understood of course that a suitable chute indicated diagrammatically at C in Fig. 4, is provided in the building for the apparatus, the various sprocket wheels being suitably supported in this chute on the side walls thereof.

The mail carrier is in the form of an oblong rectangular box 20 which is divided into a number of compartments closed on 65 one side by separate hinged doors 22. This box is fixed to and between the chains 15, having fixed projecting studs 23 which engage one link of each chain. Means are provided whereby, when the box comes opposite 70 an aperture 12 in the wall of an office or compartment the circuit through the motor 17 is opened, while this circuit is again manually closed when the door of the proper compartment is closed after the mail has 75 been removed therefrom.

To open the circuit to the motor I provide adjacent each opening 12 a cam member 25 which engages a cam projection 26 on one, 80 27, of a pair of contact members carried by the box 20 and lifts it from the other one, 28. Mounted on the box 20 and hinged to lugs 30 thereon, is a bail-like rod 31 whose intermediate portion extends along the side of the box adjacent the free edges of the 85 door 22. One of the legs of this bail has an extension 31' which carries the contact 28. Hinged to the free edge of each door is an arm 33 which normally projects up behind the bail 31 and is provided with an inclined 90 upper end indicated on the drawings at 33 which is adapted to engage the bail 31 to move the contact 28 when the door 22 is closed, the latch riding freely under the bail when the door opens, a spring 34 returning 95 it to normal position when the bail has been cleared. Each arm 33 is provided with a downwardly projecting tail-piece 33' which engages the door and holds the arm against outward movement from its normal position. 100 Adjacent the opening 13 I provide a cam disk 25^a which is pivoted further off centre than the disks 25 and has fixed co-axially thereto a projecting knob 25^b whereby it may be rotated. This cam element is so positioned as to engage the cam on the contact 27 and move the latter away from the contact 28 when the box 20 is in registry with the opening 13. When the mail box is traveling past the cams 25, or 25^a, in an inverted position, 105 as it does in two stories shown on the drawing, care must be taken in correctly position-

ing these cams, since the weight of the bail 31 forces the contact 28, and hence the spring 26 upwards, and therefore it is necessary to make adjusting corrections so that the cams 5 will be effective in breaking the circuit. The cam element 25 before referred to is in the form of an eccentrically pivoted disk suitably mounted on the outer wall, indicated at C, of the conduit or chute through 10 which the box moves and having an arm extension 25' to which are connected a pair of oppositely leading cords 36 and 37. These cords 26 and 37 may lead through suitable pipes such as those indicated at 15 in Figs. 7 and 8 of the drawing, these pipes extending along the chute to the desired points. One of these cords leads to a point adjacent the receiving opening 13 while the other leads to a point adjacent the discharge 20 opening 12. It will be understood of course that there will be a number of cord ends adjacent the receiving opening corresponding to the number of discharge openings along the route of the box. The contacts 25, 28 are connected by suitable wires respectively to a pair of spring contacts 40 and 41 mounted on the box 20 and adapted to engage insulated rails 42, 43 extending along the chute C and suitably connected to 30 the motor 17 and the source of current.

The manner of operation is as follows: Assuming the box 20 to be opposite the receiving opening 13. The mail carrier opens the proper door 22 and inserts in the compartments in the box the mail for the different offices or apartments. After he has closed the doors he turns knob 25^b moves the cam 25^a to a position allowing the contacts 27, 28 to engage one another. He also 40 pulls the proper cords 36, according to the places at which the mail is to go, and thus sets the cams 25 to operative position. The motor then starts and after the box has moved slightly the mail carrier returns cam 45 25^a to its original position. As the box comes adjacent the opening 12 the cam 26 on the contact 27 rides under the cam 25 near the said opening and opens the motor circuit. The cam 26 is indicated on the 50 drawing in the form of a point, but the cams 25 are so positioned that the point contacts with the cam through a sufficient arc of the cam, so that the circuit is not momentarily broken, but remains broken a sufficient 55 length of time to allow the inertia of the box, and motor to be overcome, thereby bringing the box to a stop. The box then stops and the person in the office or apartment opens the proper door 22, (each door 60 being provided if desired with a separate key actuated lock) and removes the mail. When the door swings open the arm 33 thereon rides under the bail 31 without lifting the latter, the spring 34 yielding to 65 allow the arm to rock on its pivot. When

the door 22 is again closed the bail 31 is engaged by the latch 33 and the contact 28 carried thereby is moved into engagement with the contact 27. The motor then starts and when the box advances and the cam 26 rides from under the cam 25 the spring contact 27 moves the contact 28 (and with it the bail 31) to its original position while still retaining its engagement therewith, it being understood that the bail has a degree of frictional engagement with its pivots sufficient both to prevent it moving when the doors 22 are opened and to ensure of the contacts remaining engaged when the cam on the former is freed. It is very obvious that even if the box is in the inverted position, the operation will be the same, provided of course that the cams are correctly positioned as before explained. The person receiving the mail then pulls the cord 37 to reset the cam in inoperative position. The box finally comes to a position adjacent the receiving opening 13 and the cam 26 engages the cam 25^a and opens the circuit. By reason of the increased degree of eccentricity of this cam it moves contact 27 an increased distance so that closing of the doors 22 does not cause contact 28 to engage it. I may if desired provide a bell in each office or apartment which is energized when the box comes to rest at the mail delivery opening of the apartment.

Having thus described my invention what I claim as new and desire to protect by Letters Patent of the United States is as follows:

1. The combination in a device of the class described, of a mail box divided into a number of compartments closed on one side by separate hinged doors, having at 105 their free edges pivoted arms which normally project up behind a bail extending along the side of the box on the top thereof, and pivotally mounted thereto, and having an extension which carries one of a pair of contacts, the other being carried by a triangular cam element also mounted on the top of said box, said pivoted arms having extensions allowing motion in one direction only, and normal position springs holding 110 said arms against the said bail.

2. The combination in a device of the class described, of a mail box divided into a number of compartments closed on one side by separate hinged doors, having at 120 their free edges pivoted arms which when said doors are closed normally project up behind a bail extending along the side of the box on the top thereof, and pivotally mounted thereto, and having an extension which carries one of a pair of contacts, the other being carried by a triangular cam element also mounted on the top of said box, said pivoted arms having extensions allowing motion in one direction only, and nor- 125 130

mal position springs holding said arms against the said bail, whereby when a door is opened the arm pivoted thereto bends to clear the bail, while when the door is closed 5 the arm lifts the bail.

3. The combination in a device of the class described, of a mail box, a bail extending along the side of the box on the top thereof, pivotally mounted thereto, and 10 having an extension which carries one of a pair of contacts, the other of said contacts being carried by a triangular cam element also mounted on the top of the said mail box.

15 4. The combination in a device of the class described, of a mail box, a bail on the top thereof, pivotally mounted thereto, and hav-

ing an extension which carries one of a pair of contacts, the other of said contacts being carried by a triangular cam element also 20 mounted on the top of the said mail box.

5. The combination in a mail delivery apparatus having an endless conveyor, and a mail box carried thereby of a bail extending along the side of the box on the top 25 thereof, pivotally mounted thereto, and having an extension which carries one of a pair of contacts, the other of said contacts being carried by a triangular cam element also mounted on the top of the said mail 30 box.

In testimony whereof I have affixed my signature.

RALPH SEVERINO.
